High Pressure Handheld Shower Head, 10-Setting Showerhead, 4.7"Detachable Showerhead Set with 5ft Hose, Adjustable Bracket and Built-in Power Wash to Clean Tub, Tile & Pets—Brush Nickel, Date First Available: Apr. 25, 2022, site visited Nov. 28, 2022 https://www.amazon.com/Pressure-10-Setting-Showerhead-Detachable-Adjustable/dp/B09YR9Y79J/ref=sr_1_7?crid=391J2T11HN0PD&keywords=hand%2Bheld%2Bshower%2Bhead&qid=1669656034&s=hi&sprefix=hand%2Bheld%2Bshower%2Bhead%2B%2Ctools%2C106&sr=1-7&th=1 (Year: 2022).*

Primary Examiner — Amy C Wierenga*Assistant Examiner* — Andrea Marie McKay(74) *Attorney, Agent, or Firm* — Nitin Kaushik(57) **CLAIM**

The ornamental design for a shower head, as shown and described.

DESCRIPTION

FIG. 1 is a front perspective view of a shower head, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of the selected portion 9 in FIG. 1.

The dashed broken lines depict portions of the shower head that form no part of the claim.

The long dash-short-dash broken lines shown in FIGS. 1 and 9 indicate cutoff boundaries for the enlarged detailed portion views and form no part of the claim.

1 Claim, 9 Drawing Sheets(56)
